Atty.

UNITED STATES PATENT OFFICE.

WALTER J. DREW, OF GRAND RAPIDS, MICHIGAN, ASSIGNOR TO THE
BISSELL CARPET SWEeper COMPANY, OF SAME PLACE.

CARPET-SWEeper.

SPECIFICATION forming part of Letters Patent No. 370,384, dated September 27, 1887.

Application filed March 12, 1887. Serial No. 230,685. (No model.)

To all whom it may concern:

Be it known that I, WALTER J. DREW, a citizen of the United States, residing at Grand Rapids, in the county of Kent and State of Michigan, have invented new and useful Improvements in Carpet-Sweepers, of which the following is a specification.

My invention relates to carpet-sweepers, and the purpose thereof is to provide novel and simple means whereby the pivotal point of attachment of the bail may be shifted from one side of the brush-shaft bearing to the other as the handle is swung over the top of the casing to operate the sweeper from opposite sides thereof.

The object of the invention is to avoid the tilting of that side of the sweeper most remote from the operator as the sweeper is drawn toward the person using it, and in this respect the invention is closely allied to and an improvement upon that contained in a separate application executed and filed by me of even date herewith and numbered in serial.

The invention consists in connecting the forked extremities of the bail to the opposite ends alternately of similarly-shaped plates, pivotally connected at their opposite alternate ends to the casing, whereby as the handle is shifted or swung from one side of the casing to the other the pivotal connection of the handle is shifted from one side of the axis of the brush-shaft to the other, thus enabling the use of the sweeper from either side of the casing and in both directions.

In the accompanying drawings, Figure 1 is an end elevation of a sweeper-casing, showing my invention applied thereto. Fig. 2 is a front elevation illustrating a portion of the casing and showing the bail attached. Figs. 3 and 4 are detail perspectives of the parts connecting the bail to the sweeper in two different positions.

In the said drawings, the reference-numeral 1 designates the sweeper-casing, which is of any usual construction. Upon the end of the casing, directly over the journals of the brush-shaft, I mount a plate, 2, by means of screws 3, said plate having a central lug, 4, projecting outwardly. From the opposite ends of the plate project lugs or ears 5, which are turned outward from the ends of the sweeper

and then parallel therewith, extending in opposite directions toward the sides of the casing.

Upon each end of the bail 6 is formed or mounted a plate, 7, which is semicircular in form, or substantially so, though this form is not essential, as the plate might be in the form of two legs of a triangle, or of three sides of a rectangle. The proportions of said plate are such that the extremities lie between the lugs 5 and in pivotal engagement therewith. Upon opposite sides of the plate 7 are placed similarly-shaped plates 8 and 9. One end of the plate 8 is pivotally connected to the end of the casing by a pivot, 8^a, and the opposite end is pivotally connected with the corresponding end of the plate 7 by a pivot, 7^a, the latter having no connection with the casing. One end of the plate 9 is connected pivotally to the casing by a pin, 9^a, set in the lug 5, and the opposite end is pivotally connected to the other extremity of the plate 7 by a pin, 7^b, which has no connection with the casing. If, now, the bail be swung to the right in Fig. 1, the plates 7 and 9 will turn upon the pin 9^a, 75 and the opposite end of the plate 7 will rise and be wholly free from connection with the casing, thereby throwing the pivotal point of connection of the bail upon one side of the brush-journal. (See Fig. 3.) If, however, 80 the handle be swung to the other side, the plates 7 and 8 will turn upon the pivot 8^a, the other end of plate 7 rising, together with the corresponding end of the plate 8, thereby shifting the pivot-point to the other side of 85 the brush-axis, as shown in Fig. 4.

The lug 4 serves as a rest to support the three plates 7, 8, and 9, and to support the bail in an upright position when raised.

Having thus described my invention, what I claim is—

1. In a carpet-sweeper, the combination, with the casing, of a bail having a branching or forking end, and correspondingly-shaped plates, one on each side thereof, said plates 95 being pivotally connected at their alternate opposite ends to the casing only, and at their other ends to the opposite extremities of the fork of the bail, substantially as described.

2. In a carpet-sweeper, the combination, 100 with the casing having a centrally-connected plate provided with a projecting rest or lug,

of a bail having divergent arms at each end, plates upon each side of said arms and co-extensive therewith, the divergent arms being pivoted to alternate opposite ends of said plates only, and the latter pivoted at their remaining ends to the casing, substantially as described.

In testimony whereof I affix my signature in presence of two witnesses.

WALTER J. DREW.
